UNITED STATES PATENT OFFICE.

HENRY DREYFUS, OF PROVIDENCE, RHODE ISLAND, ASSIGNOR TO LORSCH,
DREYFUS & CO., OF SAME PLACE.

BUTTON.

SPECIFICATION forming part of Letters Patent No. 277,999, dated May 22, 1883.

Application filed October 9, 1882. (No model.)

To all whom it may concern:

Be it known that I, HENRY DREYFUS, of the city and county of Providence, and State of Rhode Island, have invented a new and useful Improvement in Buttons; and I hereby declare that the following is a full, clear, and exact description of the same, reference being had to the accompanying drawings, forming part of this specification.

10 This invention has reference to an improvement in separable sleeve-buttons and other similar buttons worn as jewelry.

The invention consists in the combination, with the metal or other head of such a button, 15 of a stone cap provided on one side with a recess or chamber to receive the metal portion of the button, the stone cap thus forming the face and sides of the head of the button, as will be more fully set forth hereinafter.

20 Figure 1 is a perspective view of a separable button provided with my improved cap, forming the exterior of the button proper. Fig. 2 is a sectional view of a button provided with my improved stone cap.

25 In the drawings, *a* is a cut-stone cap or jewel. The various kinds of agate, blood-stone, and other stones used for buttons or similar articles, and the artificial imitations thereof, may be used for this purpose. The stone cap 30 *a* forms the face of the button, and is provided on one side with a recess or chamber, *d*, of such depth that the flanges *a'* *a'* will project a little distance below the metal head *c'* of the button to conceal said metal, and also prevent 35 it from coming in contact with the cuff or collar.

b is the post, and *c* the shoe, of the button. The recess *d* is made of such shape and dimensions as will be required to receive the metal head *c'* of the button, which varies with different styles of buttons.

40 The flanges *a'* of the stone cap may be provided with slits or notches *e*, so that the cap may extend below the pushers; or said flanges may have small holes bored through them, and 45 the pushers be passed through these holes from the inside and retained in position by springs,

as is now customary where the flanges are formed of metal.

It will be seen, on examining Fig. 2 of the drawings, that the flanges *a'* of the stone cap 50 *a* extend down beyond the metal head *c'* and pushers, so that the inner surface or face of the button is formed by the stone. The object of this is to prevent the cuff or collar from being soiled or colored, which is always the case 55 when metal comes in contact with the same, but is not so soiled or colored by the contact of the stone. The cap *a* is secured by cement or in any other suitable manner to the button-head *c'*, and forms the whole visible portion of 60 the same.

I am aware that precious stones have been used for buttons, that such stones were usually secured in settings, and also that before my invention posts have been secured to precious 65 stones by extending a portion of the shank into or through the button. All such as these I do not claim, as they are old and well known. But my improved cut-stone cap, provided with a recess or chamber to receive the metal portion 70 of the button, differs very materially from these, in that it is an article of manufacture in itself, which can be readily placed over any ordinary metal button and secured; that it can be cut in any desired form independent of the 75 form of the button, and may be ornamented by facets or otherwise; that it forms the entire visible portion of the button, and by its clean surface prevents the soiling of the linen.

Having thus described my invention, I claim 80 as new and desire to secure by Letter Patent—

In a separable button, the combination, with the head *c'* of the button, of the recessed cut-stone cap *a*, provided with slits or holes *e e*, 85 constructed to receive the pushers, as described.

In witness whereof I have hereunto set my hand.

HENRY DREYFUS.
